United States Patent Office

Des. 192,320
Patented Mar. 6, 1962

192,320

CHAIR

William James Bargen and Mathilda K. Bargen,
Waukegan, Ill.

Filed Mar. 21, 1961, Ser. No. 64,413

Term of patent 14 years

(Cl. D15—1)

The essential features of our design reside in those portions shown in full lines on the drawing.

We claim:

The ornamental design for a chair, as shown, and described.
